A. V. MARSHALL

WATER WHEEL

Filed Feb. 18, 1927

Fig. 1.

Fig. 2.

UNITED STATES PATENT OFFICE.

ALPHONSE VIRGIL MARSHALL, OF PASS CHRISTIAN, MISSISSIPPI.

WATER WHEEL.

Application filed February 18, 1927. Serial No. 169,370.

In the drawings, Fig. 1 is a plan view and Fig. 2 is an elevation of my device, with parts in section. The framework of my water wheel has two foundation pieces 1 and resting on and across these two pieces, is a sill 2. At each end of the sill are uprights 3 and joining the uprights is a cross piece 4.

Attached to upright 3 is a shield 5 which is for the purpose of preventing water from splashing. In the shield is a hole 6 through which water will flow to strike the walls of the wheel.

The wheel and axis are made in the following manner:—The axis is part solid and part hollow, the solid part 17 is supported by the bearing 8, the upper part 19 is hollow and passes through cross piece 4 where it is also supported by a bearing 8. At the top of the solid part is a nut 18 to hold the wheel tight. The shaft 17 is also provided with a thrust bearing 7 and a pulley from which power is taken off. Through the wall of the hollow part is a hole the purpose of which will be mentioned hereafter.

This makes the axis.

The wheel is made of two annular disks 23, 24 of the same size, with two hoops or bands 13, 14. The hoops must be of the same width but differ in diameter. The hoops will be placed within one another and laid on one disk. This disk will be the bottom of the wheel. The other disk will be laid on top of the hoops and will be called the top of the wheel, and between the hoops

will be a hollow space 11 which is for the purpose of holding water. The disks must be made larger in diameter than the largest hoop. This will give a groove 10 all around the outside of the wheel. In this groove spaced apart will be solid walls 9. Against these walls the water that flows through nozzle 6 will strike and cause the wheel to turn. On the bottom of the wheel will be a valve 12 to drain the space 11. On top of wheel will be a tube 16 for air to escape from said space, 45 also a hole 15 to receive a water pipe 21 which runs over to hole 20 in the wall of the hollow part 19 of the axis which has been mentioned above, in and up the hollow of axis to funnel 22.

By turning the wheel like a top on a small point friction is reduced, the wheel being empty makes starting easy, filling while in operation makes the wheel heavy and powerful.

I claim:—

In a water wheel the combination of a framework, a vertical shaft journaled therein, a rotor secured to said shaft, comprising a pair of spaced parallel annular disks and a pair of spaced concentric bands forming with said disks an annular chamber, spaced vanes secured to the outer of said bands, means for directing a jet of fluid against said vanes and means for introducing fluid into said annular chamber while said wheel is in motion.

ALPHONSE VIRGIL MARSHALL.
